HYDRAULIC TRANSMISSION

James K. Douglas, Milwaukee, Wis., assignor to
 The Oilgear Company, Milwaukee, Wis., a corporation of Wisconsin

Application July 9, 1934, Serial No. 734,326

19 Claims. (Cl. 60—52)

This invention relates to hydraulic transmissions of the type employed to move a tool or a piece of work at different rates during different parts of a cycle of operation.

5 In certain operations, such as drilling, it is desirable to feed the tool through the work at a given rate and then, at a certain point in the operation, suddenly reduce the feed rate. For example, a drill should be fed through the work 10 at the highest practicable rate in order to obtain maximum production from the drilling machine but, if the high feed rate is maintained after the point of the drill breaks through the work, the drill will usually lunge forward and thread itself 15 through the remaining portion of the metal which is too strong to be torn away from the edges of the hole by the drill, thereby causing the drill to break or to stall.

The present invention has as an object to provide a hydraulic transmission in which the motor will operate at a relatively fast rate as long as the work performed by it causes the pump to create a pressure above a given value and will have its rate of operation automatically reduced upon pump pressure falling below that value.

20 Another object is to provide a hydraulic transmission in which the motor will operate at one speed when pressure exceeds a certain value and at a lower speed when pump pressure falls below that value, and in which each of those speeds is maintained within close limits.

Another object is to provide a hydraulic transmission of this character which is positive and precise in operation.

25 Another object is to provide a hydraulic transmission with an automatic displacement varying mechanism which is simple in construction and which may be readily and accurately adjusted.

Other objects and advantages will appear from 30 the description hereinafter given of a hydraulic transmission in which the invention is embodied.

According to the invention in its general aspect, the transmission has its pump provided with a displacement varying element which is urged toward full displacement position by a force proportional to pump pressure, and a stop which limits the movement of the element in that direction to thereby determine the fast feed rate of the motor. The displacement varying element is urged toward zero displacement by means which 35 yield when pump pressure exceeds a given value to thereby permit the pump to deliver liquid at the fast feed rate but which is capable of moving the displacement varying element toward zero displacement position when pump pressure

falls below the given value to thereby cause the pump to deliver liquid at a slow feed rate.

The invention is exemplified by the hydraulic transmission illustrated in the accompanying drawing in which the single figure shows schematically the invention applied to a drill press.

The transmission consists primarily of a hydraulic motor 1, a pump 2 for supplying liquid to the motor, mechanism 3 for varying pump displacement, a valve 4 for controlling the flow of liquid to and from the motor, and suitable fluid channels connecting the valve to the motor and to the pump.

The motor is shown as being of the ordinary reciprocating type and as having its cylinder fastened to the frame 5 of a drill press. The motor cylinder has a piston 6 fitted therein and provided with a piston rod 7 which is connected to the spindle 8 of the drill press through an antifriction thrust bearing 9 to permit the spindle to rotate without rotating the rod 7 or the piston 6.

The spindle 8 is rotated by a belt 10 which engages a pulley 11 fixed upon the spindle inside a bearing 12 carried by the frame 5.

The drill press is provided with a work table 13 to support a piece of work 14 which is to be operated upon by a drill 15 fastened to the spindle 8 to rotate therewith.

The pump 2 is of a well known type and a description or a detailed illustration thereof is not necessary to an understanding of the present invention. It is sufficient to state that the pump has its cylinders arranged radially in a cylinder barrel 16 and its pistons in contact with the annular inner surface of an adjustable thrust member 17. The cylinder barrel ordinarily rotates at a constant speed upon a stationary valve shaft or pintle 18 through which liquid flows to and from the cylinders. The displacement of the pump, and consequently the rate at which the drill 15 is advanced into the work 14, depends upon the distance which the axis of the thrust member 17 is offset from the axis of the pintle 18.

When the axis of the thrust member 17 coincides with the axis of the cylinder barrel, the pump is at zero stroke and no liquid will be delivered thereby. When the axis of the thrust member is moved to one side of the axis of the cylinder barrel, the pump will deliver liquid at a rate dependent upon the distance between the axes. If it is moved above the cylinder barrel axis as shown in the drawing, the pump will deliver liquid into a discharge pipe 19 and liquid

will flow into the pump cylinders through a return pipe 20.

The pipes 19 and 20 have one end of each connected to the pintle 18 and the other end of each 5 connected to the valve 4 which is connected by pipes 21 and 22 to opposite ends of the motor 1 to control the operation thereof.

In the arrangement shown, the volume of liquid delivered into the pipe 19 is sufficient only for 10 operating the motor at limited speeds, that is, at speeds suitable for feeding the drill into and through the work, but the pump ordinarily has a larger capacity gear pump incorporated therein or associated therewith for driving the motor at 15 rapid traverse speed. The valve 4 controls the delivery of liquid to the motor from both of the pumps. Since the gear pump forms no part of the present invention, it has been omitted from the drawing in order to simplify the same.

20 The thrust member 17 is urged toward maximum displacement position by two springs 23 which have sufficient strength to support the thrust member 17 and to move it upward when it is arranged in a vertical position, as shown in 25 the drawing.

The upward movement of the thrust member is limited by a positive stop which is shown as a cam 24 fixed upon a control shaft 25. Rotation of the shaft 25 in one direction will cause the cam 30 24 to move the thrust member 17 downward against the action of the springs 23 and thereby decrease pump displacement, and rotation of the shaft in the opposite direction will permit the springs 23 to move the thrust member 17 upward and thereby increase pump displacement.

All power pumps have as an inherent characteristic thereof an internal leakage or slip which varies directly in accordance with variation in pump pressure. In order to compensate for this 40 variation in slip, the thrust member 17 is ordinarily urged by a force proportional to pump pressure toward maximum displacement position against the resistance of spring means which yields as pump pressure increases.

45 As shown, the thrust member 17 is urged upward by a fluid actuated plunger 26 against a spring 27. The plunger 26 is fitted in a stationary cylinder 28 which is connected to the discharge pipe 19 by a pipe 29 so that the plunger 26 is subjected at all times to pump pressure. The spring 27 is shown as consisting of a stack of Belleville spring washers arranged in a socket 30 which is carried by the thrust member 17 and has a plunger 31 fitted therein and normally in contact with both the spring 27 50 and the cam 24.

When the pump is delivering liquid, the thrust member 17 is urged upward by the plunger 26 with a force proportional to pump pressure, and it is also urged upward by the springs 23. As 60 pump pressure increases and causes an increase in slip, the force exerted by the plunger 26 increases and compresses the spring 27 slightly, thereby increasing pump displacement by an amount which is just sufficient to compensate for the increase in slip.

The thrust member 17 is urged downward by the displacement varying mechanism 3. This mechanism is provided with an internally threaded socket 32 which is carried by the pump casing in alignment with the plunger 31 and has an externally threaded cylinder 33 threaded therein. The cylinder 33 is provided at its lower end with an annular flange 34 which functions as a stop to 75 limit the distance through which the thrust mem-

ber 17 may be moved by the displacement varying mechanism 3.

The cylinder 33 has threaded therein an externally threaded cylinder 35 which is closed at its upper end by an adjusting knob 36. A helical compression spring 37 is arranged inside the cylinders 33 and 35 with its upper end in contact with the underside of the knob 36 and its lower end in contact with a push pin 38 which extends downward through the socket 32 and has its head 39 arranged inside the cylinder 33 in contact with the spring 37 and overlapping the flange 34.

The spring 37 transmits a downward pressure upon the thrust member 17 through a bifurcated pressure member 40 which straddles the control 15 shaft 25 and has its upper end in contact with the push pin 38 and its lower end in contact with the plunger 31.

The spring 37 tends to move the thrust member 17 downward and thereby cause the pump to deliver liquid at a rate lower than the rate determined by the adjustment of the cam 24, but when the pump is delivering liquid at a pressure above a predetermined value, the upward force exerted by the plunger 26 added to the upward force exerted by the springs 23 exceeds the downward force exerted by the spring 37 and holds the plunger 31 in contact with the cam 24 to cause the pump to deliver liquid at the predetermined fast feed rate.

When pump pressure falls below the predetermined value, the downward force exerted by the spring 37 overcomes the upward forces exerted by the plunger 26 and the springs 23 and moves the thrust member downward until the head 39 of the pin 38 engages the flange 34, thereby causing the pump to deliver liquid at a slow feed rate determined by the position of the flange 34.

The pump pressure, at which the pump will automatically change from one feed rate to the other, is determined by the tension of the spring 37 which may be adjusted by turning the knob 36 to vary the distance between its underside and the head 39 of the pin 38. This pressure may be indicated by suitable graduations cut into the 45 unthreaded surface of the cylinder 35 at 41 to register with the top of the cylinder 33.

The slow feed rate is determined by the position of the flange 34 which limits the downward movement of the pin 38 and, consequently, the 50 downward movement of the thrust member 17. This feed rate may be indicated by suitable graduations cut in the unthreaded surface of the cylinder 33 at 42 to register with the top of the socket 32. The position of the flange 34 may be 55 adjusted by turning the cylinder 33 which, for this purpose, has an annular adjusting knob 43 fixed to its upper end.

The knob 43 may be turned to adjust the pump to the exact slow feed rate desired and then held 60 stationary while the knob 36 is turned to adjust the spring 37 to the exact tension required to cause the pump to change from fast feed rate to slow feed rate at the instant that pump pressure drops to a predetermined value but, in the majority of installations, it is desirable to keep the reading on the graduations 41 unchanged when adjusting the slow feed rate of the pump. Consequently, the knob 43 is ordinarily provided with a spring detent 44 which engages the cylinder 35 70 and causes it to turn in unison with the cylinder 33.

In the majority of variable displacement pumps employed for operating the feed mechanisms of machine tools, a slight variation in the length 75

of the stroke of the pump will cause a relatively large variation in the volumetric delivery of the pump. For example, if the thrust member 17 should be moved slightly, pump output will be varied considerably. Consequently, only a slight axial movement of the cylinder 33 is necessary to make a considerable variation in the slow feed rate. This axial movement is so slight that, if the spring 37 is relatively long as shown in the drawing, the cylinder 35 may turn with the cylinder 33 and cause only a slight variation in the tension of the spring 37 and, therefore, only a slight variation in the pressure at which the pump will change from fast feed rate to slow feed rate.

When the drill 15 is advanced into contact with the work 14, the resistance of the work to the entry of the drill point causes pump pressure to rise sufficiently to enable the plunger 26 to move the thrust member 17 upward until the plunger 26 engages the cam 24. The drill will then be fed into the work at a substantially uniform fast feed rate which is determined by the adjustment of the cam 24.

If the resistance of the work should be such as to cause pump pressure to rise still higher and thereby cause the slip of the pump to increase, the spring washers 27 will yield slightly under the additional force exerted by the plunger 26 due to the increase in pump pressure, thereby permitting the thrust member 17 to move upward and increase pump delivery by an amount substantially equal to the increase in slip. The drill is thus fed into the work at a fast feed rate which remains substantially constant as long as the drill meets sufficient resistance.

When the drill has so nearly completed its operation that only a thin shell of metal remains under it, this thin shell will yield under the thrust of the drill and cause pump pressure to drop, thereby decreasing the upward force exerted by the plunger 26 upon the thrust member 17 and enabling the spring 37 to move the thrust member 17 downward and cause the pump to deliver liquid to the motor 1 at the slow feed rate determined by the position of the flange 34. The drill is then advanced slowly through the remaining part of the work without danger of damage to the drill or to the machine. The drawing shows the pump delivering liquid at the fast feed rate and the thin shell of metal under the drill starting to bend which will cause pump pressure to drop.

The transmission herein described is susceptible of various modifications and adaptations without departing from the scope of the invention as hereafter claimed.

The invention is hereby claimed as follows:

1. A hydraulic transmission, comprising a hydraulic motor, a variable displacement pump for supplying liquid to said motor and having an element movable to vary pump displacement and thereby vary the speed of said motor, fluid operated means responsive to pressure created by said pump for moving said element in a direction to increase pump delivery, a stop for limiting the movement of said element in said direction, and other means for moving said element in a direction to decrease pump delivery; said other means being yieldable under the action of said fluid operated means when pump pressure exceeds a predetermined value to thereby enable said pump to operate said motor at a rate of speed limited by said stop and said other means being capable of moving said element against the action of said fluid operated means when pump pressure falls below said value to thereby cause said pump to operate said motor at a lower rate of speed, but not less than the rate determined by the position of said abutment, and means operable when pump pressure exceeds said predetermined value for compensating for variations in the slip of said pump.

pressure falls below said value to thereby cause said pump to operate said motor at a lower rate of speed.

2. A hydraulic transmission, comprising a hydraulic motor, a variable displacement pump for supplying liquid to said motor and having an element movable to vary pump displacement and thereby vary the speed of said motor, fluid operated means responsive to pressure created by said pump for moving said element in a direction to increase pump delivery, a stop for limiting the movement of said element in said direction, other means for moving said element in a direction to decrease pump delivery, and an abutment for limiting the extent of movement of said element by said other means; said other means being yieldable under the action of said fluid operated means when pump pressure exceeds a predetermined value to thereby enable said pump to operate said motor at a rate of speed limited by said stop and said other means being capable of moving said element against the action of said fluid operated means when pump pressure falls below said value to thereby cause said pump to operate said motor at a lower rate of speed, but not less than the rate determined by the position of said abutment.

3. A hydraulic transmission, comprising a hydraulic motor, a variable displacement pump for supplying liquid to said motor and having an element movable to vary pump displacement and thereby vary the speed of said motor, fluid operated means responsive to pressure created by said pump for moving said element in a direction to increase pump delivery, a stop for limiting the movement of said element in said direction, other means for moving said element in a direction to decrease pump delivery; said other means being yieldable under the action of said fluid operated means when pump pressure exceeds a predetermined value to thereby enable said pump to operate said motor at a rate of speed limited by said stop and said other means being capable of moving said element against the action of said fluid operated means when pump pressure falls below said value to thereby cause said pump to operate said motor at a lower rate of speed, and means operable when pump pressure exceeds said predetermined value for compensating for variations in the slip of said pump.

4. A hydraulic transmission, comprising a hydraulic motor, a variable displacement pump for supplying liquid to said motor and having an element movable to vary pump displacement and thereby vary the speed of said motor, fluid operated means responsive to pressure created by said pump for moving said element in a direction to increase pump delivery, a stop for limiting the movement of said element in said direction, other means for moving said element in a direction to decrease pump delivery, and an abutment for limiting the extent of movement of said element by said other means; said other means being yieldable under the action of said fluid operated means when pump pressure exceeds a predetermined value to thereby enable said pump to operate said motor at a rate of speed limited by said stop and said other means being capable of moving said element against the action of said fluid operated means when pump pressure falls below said value to thereby cause said pump to operate said motor at a lower rate of speed, but not less than the rate determined by the position of said abutment, and means operable when pump pressure exceeds said predetermined value for com-

pensating for variations in the slip of said pump.

5. A hydraulic transmission, comprising a hydraulic motor, a variable displacement pump for supplying liquid to said motor and having an element movable to vary pump displacement and thereby vary the speed of said motor, fluid operated means responsive to pressure created by said pump for moving said element in a direction to increase pump delivery, a stop for limiting the movement of said element in said direction, other means for moving said element in a direction to decrease pump delivery; said other means being yieldable under the action of said fluid operated means when pump pressure exceeds a predetermined value to thereby enable said pump to operate said motor at a rate of speed limited by said stop and said other means being capable of moving said element against the action of said fluid operated means when pump pressure falls below said value to thereby cause said pump to operate said motor at a lower rate of speed, and spring means arranged between said element and said stop for compensating for variations in the slip of said pump during periods in which pump pressure exceeds said predetermined value.

6. A hydraulic transmission, comprising a hydraulic motor, a variable displacement pump for supplying liquid to said motor and having an element movable to vary pump displacement and thereby vary the speed of said motor, fluid operated means responsive to pressure created by said pump for moving said element in a direction to increase pump delivery, a stop for limiting the movement of said element in said direction, other means for moving said element in a direction to decrease pump delivery, an abutment for limiting the extent of movement of said element by said other means; said other means being yieldable under the action of said fluid operated means when pump pressure exceeds a predetermined value to thereby enable said pump to operate said motor at a rate of speed limited by said stop and said other means being capable of moving said element against the action of said fluid operated means when pump pressure falls below said value to thereby cause said pump to operate said motor at a lower rate of speed, but not less than the rate determined by the position of said abutment, and spring means arranged between said element and said stop for compensating for variations in the slip of said pump during periods in which pump pressure exceeds said predetermined value.

7. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction, a plunger for moving said element in the opposite direction to decrease pump delivery, and a spring acting independent of said stop for urging said plunger toward said element and adapted to yield under the action of said fluid actuated means when pump pressure exceeds a predetermined value and to move said element against the action of said fluid operated means when pump pressure falls below said value.

8. A hydraulic transmission, comprising a hydraulic motor, a variable displacement pump connected to said motor for operating the same and provided with a displacement varying element, fluid operated means responsive to pump pres-

sure for moving said element in a direction to increase pump delivery, a stop for limiting the movement of said element in said direction, a plunger for moving said element in the opposite direction to decrease pump delivery, a spring acting independent of said stop for urging said plunger toward said element and adapted to yield under the action of said fluid actuated means when pump pressure exceeds a predetermined value and to move said element against the action of said fluid operated means when pump pressure falls below said value, and means for limiting the movement of said element in a direction to reduce pump delivery.

9. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction, a plunger for moving said element in the opposite direction to decrease pump delivery, a spring acting independent of said stop for urging said plunger toward said element and adapted to yield under the action of said fluid actuated means when pump pressure exceeds a predetermined value and to move said element against the action of said fluid operated means when pump pressure falls below said value, and means arranged between said stop and said element for compensating for variations in pump delivery due to variations in pump pressure above a predetermined pressure.

10. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction, a plunger for moving said element in the opposite direction to decrease pump delivery, a spring acting independent of said stop for urging said plunger toward said element and adapted to yield under the action of said fluid actuated means when pump pressure exceeds a predetermined value and to move said element against the action of said fluid operated means when pump pressure falls below said value, means for limiting the movement of said element in a direction to reduce pump delivery, and means arranged between said stop and said element for compensating for variations in pump delivery due to variations in pump pressure above a predetermined pressure.

11. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction to thereby limit the maximum output of said pump, a plunger for moving said element in the opposite direction to decrease pump delivery, and a spring acting independent of said stop for urging said plunger toward said element and adapted to yield under the action of said fluid operated means when pump pressure exceeds a predetermined value and to move said element against the action of said fluid operated means when

pump pressure falls below said predetermined value.

12. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement 10 of said element in said direction to thereby limit the maximum output of said pump, a plunger for moving said element in the opposite direction to decrease pump delivery, a stationary support, a spring retainer carried by said support, and a spring arranged within said retainer for urging said plunger toward said element and adjustable as to tension by adjustment of said retainer, said spring being adapted to yield under the action of said fluid operated means when pump pressure exceeds a predetermined value and to move said 20 element against the action of said fluid operated means when pump pressure falls below said predetermined value.

13. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction to thereby limit the maximum output of said pump, a plunger for moving said element in the opposite direction to decrease pump delivery, a stationary support, a spring retainer carried by said support, and a spring arranged within said retainer for urging said plunger toward said element and adjustable as to tension by adjustment of said retainer, said spring being adapted to yield under the action of said fluid operated means when pump pressure exceeds a predetermined value and to move said element against the action of said fluid operated means when pump pressure falls below said predetermined value, and means carried by said retainer for limiting the movement of said plunger to thereby limit the reduction in pump delivery.

14. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction to thereby limit the maximum output of said pump, a plunger for moving said element in the opposite direction to decrease pump delivery, a stationary support, a cylinder threaded into said support and provided with an abutment to limit the movement of said plunger whereby rotation of said cylinder in said support will vary the distance said plunger can move said element, a spring arranged within said cylinder for urging said plunger toward said element, and a second cylinder threaded into said first cylinder whereby rotation of said second cylinder will adjust the tension of said spring, said spring being adapted to yield under the action of said fluid operated means when pump pressure exceeds a predetermined value and to move said element against the action of said fluid operated means when pump pressure falls below said predetermined value.

15. A hydraulic transmission, comprising a

hydraulic motor, a variable displacement pump connected to said motor for operating the same and provided with a displacement varying element, fluid operated means responsive to pump pressure for moving said element in a direction to increase pump delivery, a stop for limiting the movement of said element in said direction to thereby limit the maximum output to said pump, spring means arranged between said stop and said element for compensating for variations in the slip of said pump due to variations in pump pressure above a predetermined pressure, a plunger acting through said spring means for moving said element in the opposite direction to decrease pump delivery, and a spring acting in- 15 dependent of said stop for urging said plunger toward said element and adapted to yield under the action of said fluid operated means when pump pressure exceeds a predetermined value and to move said element against the action of said fluid operated means when pump pressure falls below said predetermined value.

16. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction to thereby limit the maximum output of said pump, spring means arranged between said stop and said element for compensating for variations in the slip of said pump due to variations in pump pressure above a predetermined pressure, 35 a plunger acting through said spring means for moving said element in the opposite direction to decrease pump delivery, a stationary support, a spring retainer carried by said support, and a spring arranged within said retainer for urging 40 said plunger toward said element and adjustable as to tension by adjustment of said retainer, said spring being adapted to yield under the action of said fluid operated means when pump pressure exceeds a predetermined value and to move 45 said element against the action of said fluid operated means when pump pressure falls below said predetermined value.

17. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction to thereby limit the maximum output of said pump, spring means arranged between said stop and said element for compensating for variations in the slip of said pump due to variations in 60 pump pressure above a predetermined pressure, a plunger acting through said spring means for moving said element in the opposite direction to decrease pump delivery, a stationary support, a spring retainer carried by said support, a spring 65 arranged within said retainer for urging said plunger toward said element and adjustable as to tension by adjustment of said retainer, said spring being adapted to yield under the action of said fluid operated means when pump pressure exceeds a predetermined value and to move 70 said element against the action of said fluid operated means when pump pressure falls below said predetermined value, and means carried by said retainer for limiting the movement of said 75

plunger to thereby limit the reduction in pump delivery.

18. A hydraulic transmission, comprising a hydraulic motor, a variable displacement pump connected to said motor for operating the same and provided with a displacement varying element, fluid operated means responsive to pump pressure for moving said element in a direction to increase pump delivery, a stop for limiting the movement of said element in said direction to thereby limit the maximum output of said pump, spring means arranged between said stop and said element for compensating for variations in the slip of said pump due to variations in pump pressure above a predetermined pressure, a plunger acting through said spring means for moving said element in the opposite direction to decrease pump delivery, a stationary support, a cylinder threaded into said support and provided with an abutment to limit the movement of said plunger whereby rotation of said cylinder in said support will vary the distance said plunger can move said element, a spring arranged within said cylinder for urging said plunger toward said element, and a second cylinder threaded into said first cylinder whereby rotation of said second cylinder will adjust the tension of said spring, said spring being adapted to yield under the action of said fluid operated

means when pump pressure exceeds a predetermined value and to move said element against the action of said fluid operated means when pump pressure falls below said predetermined value.

19. A hydraulic transmission, comprising a hydraulic motor, a variable displacement pump for supplying liquid to said motor and having an element movable to vary pump displacement and thereby vary the speed of said motor, pressure and discharge channels connecting said pump to said motor, a fluid motor connected to said pressure channel for moving said element in a direction to increase pump delivery in response to pressure created by said pump, a stop for limiting the movement of said element in said direction, and other means for moving said element in a direction to decrease pump delivery; said other means being yieldable under the action of said fluid motor when pump pressure exceeds 20 a predetermined value to thereby enable said pump to operate said hydraulic motor at a rate of speed which is limited by said stop and said other means being capable of moving said element against the action of said fluid motor when 25 pump pressure falls below said value to thereby cause said pump to operate said hydraulic motor at a lower rate of speed.
